UNITED STATES PATENT OFFICE.

JAMES L. BROWN, OF LANCASTER, PENNSYLVANIA.

DESIGN FOR AN UMBRELLA OR PARASOL CASE.

SPECIFICATION forming part of Design No. 28,465, dated April 12, 1898.

Application filed February 12, 1898. Serial No. 670,147. Term of patent 7 years.

To all whom it may concern:

Be it known that I, JAMES L. BROWN, a citizen of the United States, and a resident of the city and county of Lancaster and State of Pennsylvania, have invented and produced a new and useful Design for Umbrella or Parasol Cases, of which the following is a clear and sufficient specification, reference being had to the drawing annexed.

My design consists of an umbrella or parasol case which has a series of parallel flutings A A rising above the surface of the case and extending crosswise of the same and extending from top to bottom in a gradually-tapering arrangement of flutes.

Having now described my design, what I claim, and desire to secure by Letters Patent, is—

The design for an umbrella and parasol case, substantially as shown and described.

JAS. L. BROWN.
